UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

PRINTING-PLATE-SHAVING MACHINE.

1,212,730.

Specification of Letters Patent. Patented Jan. 16, 1917.

Application filed July 21, 1909. Serial No. 508,866.

To all whom it may concern:

Be it known that I, HOWARD M. BARBER, a citizen of the United States, and resident of Stonington, in the county of New London 5 and State of Connecticut, have invented new and useful Improvements in Printing-Plate-Shaving Machines, of which the following is a specification.

This invention relates to improvements in 10 printing plate shaving machines and has for one of its objects to provide a machine of this character in which a brake for the reciprocating bed and the motor are both under the control of the movements of the bed 15 whereby the brake is applied and the motor stopped automatically at the rearward and forward limits of movement of the bed.

A further object is to provide means for 20 automatically raising the knife carrying head as the bed reaches the limit of its rearward movement and for automatically lowering the head as the bed reaches the limit of its forward movement.

A further object is to provide manually 25 operated means for raising the knife carrying head and for stopping the motor at any desired point in the rearward movement of the reciprocating bed.

A further object is to provide certain novel 30 features in the construction, form and arrangement of the several parts whereby all lost motion is obviated in the knife carrying head thus insuring a shaving of the printing plate with the utmost accuracy.

35 In the accompanying drawings, Figure 1 represents the shaving machine in side elevation, the several parts being shown in full lines in the position which they assume when the machine is at rest with the reciprocating 40 bed at the limit of its forward movement and in dotted lines when the reciprocating bed is at the limit of its rearward movement, Fig. 2 is a top plan view of the same, Fig. 3 is a front end view of the machine, Fig. 4 is a detail view showing more clearly the brake 45 for stopping the reciprocating bed at the limits of its movement, Fig. 5 is a section taken in the plane of the line A—A of Fig. 4, looking in the direction of the arrows, Fig. 6 is an enlarged detail longitudinal 50 vertical section, Fig. 7 is a detail transverse section through a portion of the machine showing one of the plate pressure rolls, Fig. 8 is a fragmentary horizontal section taken 55 in the plane of the line B—B of Fig. 6, look-

ing in the direction of the arrows, Fig. 9 is a detail transverse section taken in the plane of the line C—C of Fig. 6, looking in the direction of the arrows, and Fig. 10 is a detail plan view partially in section showing 60 the connections for automatically applying the brake to limit the backward and forward movements of the bed.

The bed frame of the machine is denoted by 1 and its supporting legs by 2. The bed frame is provided with ways 3, for guiding the reciprocating bed 4 in its forward and rearward movements. The reciprocating bed 4 is provided with a rack 5, which rack is engaged by a reversing pinion 6 fixed 70 to a cross shaft 7 suitably mounted in the bed frame 1. This cross shaft 7 is driven by a worm and gear connection 8, 9, from a drive shaft 10, which shaft is in turn driven from any suitable source of power such, for 75 instance, as a reversing motor 11, by a belt and pulley connection 12, 13, 14.

A motor controlling lever 15 is fixed to a cross rock shaft 16 supported by suitable 80 hangers 17 from longitudinal tie rods 18 carried by the legs 2 of the framing. The motor controlling lever 15 is arranged to control the direction of movement of the motor shaft 19 through a controller 20 of any suitable design, the pinion 21 of which 85 controller meshes with the teeth of a rack bar 22 connected to the lever 15.

It is to be understood that in the arrangement of the parts as herein shown, when the lever is swung forwardly the motor shaft 90 will be driven in a direction to cause the reversing pinion 6 to drive the reciprocating bed rearwardly; when the lever is moved rearwardly the motor shaft will be driven in the reverse direction to cause the pinion 6 95 to drive the bed forwardly, and when the lever is in its intermediate position the controller will be in its neutral position and the movement of the motor shaft stopped.

The shaving knife is denoted by 23 and 100 it is adjustable by means of screws 26 and clamped in its adjustments by means of set screws 25 upon a member 24 of the vertically movable knife carrying head 27 which head is suitably mounted between the upris- 105 ing sides 28 of the bed frame 1. The mem- ber 24 of the knife carrying head 27 is in turn adjustably mounted upon the said knife carrying head as follows: An approximate adjustment of this knife carrying member 110

24 is provided for by means of vertical adjusting screws 29, 30, rotatably mounted in the knife carrying head 27, which screws pass through interiorly threaded lugs 31, 32, projecting through vertically elongated recesses 33, 34, in the knife carrying head 27. Coil springs 35, 36, surround the screws 29, 30, and are interposed between the bottoms of the recesses 33, 34, and the lugs 31, 32, respectively, for eliminating all lost motion between the said lugs and screws. These screws 29, 30, are provided with spur gears 37, 38, which mesh with a spur gear 39 fixed to the shaft 40 of a hand wheel 15 41 mounted on the knife carrying head 27.

A micrometer adjustment of the knife carrying member 24 is provided for through a worm 42 carried by a horizontal hand shaft 43 mounted on the knife carrying head 20 27, which worm may be moved into and out of mesh with a worm gear 44 fixed on the shaft 40 of the hand wheel 41. In the present instance, a hand lever 45 is provided for this purpose.

25 The crank handle of the shaft 43 is denoted by 46.

A suitable disk scale 47 may be provided on the shaft 40 for accurately adjusting the vertical position of the knife with respect to the knife carrying head to a predetermined point. The knife is clamped rigidly to the knife carrying head in its predetermined vertical adjustment by providing screw bolts 48 which enter the rear ends 30 of the lugs 31, 32, between the heads of which bolts and the back face of the head 27 are interposed clamping plates 49. Vertical slots 50, 51, are provided through the rear wall of the recesses 33, 34, into which 40 the rear ends of the lugs 31, 32, extend.

The knife carrying head 27 is moved toward and away from the traveling bed by the following means:—A rock shaft 52 is mounted in the bed frame 1 and beyond the 45 bed frame upon both sides of the machine the shaft is provided with eccentric portions 53, 54, journaled in boxes 55, 56, which rest upon the horizontal bottom walls of the loops 57, 58, of frames 59, 60, secured to the

50 opposite ends of the knife carrying head 27 as, for instance, by screw bolts 61, 62. The lower ends of these loop frames 59, 60, are guided by pins 63, 64, supported in brackets 65, 66, projecting from the bed frame 1.

55 The knife carrying head 27 is pressed upwardly under the strong tension of springs 67, 68, which also serve to hold the horizontal bottom walls of the loops 57, 58, of the frames 59, 60, snugly in engagement with 60 the boxes 55, 56, carried by the eccentric portions 53, 54, of the cross rock shaft 52.

Upon one side of the machine an operating lever 69, for manually raising the knife carrying head at any time in the rearward 65 movement of the bed, is fixed to a concentric

pin 70 extending outwardly from the eccentric portion 54 of the shaft 52.

The means for automatically controlling the raising and lowering of the knife carrying head by the movement of the reciprocating bed so that the shaving knife will be lowered before the bed starts on its rearward movement and raised before the bed starts on its forward movement, is constructed, and arranged as follows:—On the side of the machine upon which the levers 15 and 69 are located, the reciprocating bed 4 is provided with a fixed abutment 71 at its forward end and a longitudinally adjustable abutment 72 near its rear end, the adjustment of 75 which abutment 72 is provided for in the present instance by a removable pin 73 arranged to engage any one of a series of holes 74 along the side of the reciprocating bed 4.

As the reciprocating bed 4 approaches the 80 limit of its rearward movement, the front abutment 71 will engage the free end of an arm 75 mounted upon a stud shaft 76 carried by the bed frame 1. When the reciprocating bed 4 approaches the limit of its 85 forward movement, the abutment 72 will engage an arm 77 carried by a hub 78 mounted upon a stud shaft 79. A link bar 80 connects the arms 75 and 77 so that these 90 two arms are moved together.

The hub 78 is further provided with an arm 81 which is connected to an arm 82 on the hub of the lever 69 by a connecting link 83 so that the shaft 52 is rocked by the 95 rocking movement of the arms 75 and 77 100 for automatically raising and lowering the knife carrying head.

The lever 15 is connected to the arm 75 by a lost motion connecting link 84, which link has a pin and slot connection 85, 86, 105 with the said lever 15. This lost motion connection between the controlling lever 15 and the arm 75 permits the operator to throw the controlling lever 15 into its neutral position at any time during the 110 rearward movement of the reciprocating bed 4 whenever the lever 69 is raised by hand for manually lifting the knife carrying head.

The rearward and forward movements of 115 the bed are stopped by a brake mechanism under the control of the bed as follows:—A band brake is located on the shaft 10, the brake drum being denoted by 87 and the brake band by 88. The band tightening 120 lever is denoted by 89 and it is engaged by a double cam 90 carried by an arm 91 fixed to a cross rock shaft 92 mounted in the bed frame 1 at the rear end of the machine. This shaft 92 is provided with a depending 125 arm 93 which is connected by a link rod 94 with an uprising arm 95 fixed to the rock shaft 16 upon which the controlling lever 15 is also fixed. This arm 95 is located at 130 the opposite side of the machine from the

lever 15 and it is provided with a rearwardly extended bar 96 resting in suitable guides 97, 98, on the bed frame 1, along the side of the reciprocating bed 4. This bar 96 is provided with uprising lugs 99, 100.

The reciprocating bed 4 is provided with a front fixed abutment 101 corresponding to the abutment 71 and a longitudinally adjustable rear abutment 102 corresponding to 10 the abutment 72. This rear abutment 102 is shown as a pin which may be inserted through any one of a series of holes 103 located along the side of the reciprocating bed 4. These abutments 101, 102, are so 15 placed that they will engage the uprising lugs 99, 100, respectively, of the rearwardly extended bar 96 for moving the several arms and lever to apply the brake to stop the movement of the bed and for throwing the 20 controlling lever 15 into its neutral position to stop the operation of the motor, as will hereinafter appear in descriptions of the operation of the machine.

Suitable spring pressed rollers 104, 105, 25 are arranged to the front and rear of the cutting edge of the shaving knife 23 in position to exert their pressure upon the back of the printing plate being shaved. Each of these rollers 104, 105, is provided with 30 shanks 106, 107, extending upwardly through the knife carrying member 24, springs 108, 109, being provided for yieldingly holding the rollers at the limit of their downward movement and adjusting 35 nuts 110, 111, being provided for adjustably limiting the downward movement of the said rollers.

The downward movement of the knife carrying head 27 is limited by vertically 40 adjustable bolts 112 which have screw threaded engagements with lugs 113, on the uprising sides 28 of the bed frame 1, the heads of which bolts are adjusted into position to be engaged by the under side of a 45 rearwardly extended shelf 114 of the knife carrying head as the head reaches approximately its lowest position, thus rigidly supporting the head in its lowered position during the shaving operation. Lock nuts 50 115 on the bolts 112 serve to lock the bolts in their proper adjusted position with respect to the knife carrying head.

In operation, supposing the parts to be in the position shown in full lines, Fig. 1, 55 with the reciprocating bed at the limit of its forward movement, the controlling lever 15 in its neutral position and the band brake applied and the motor at rest: The controlling lever 15 is swung forwardly into 60 the position indicated by the line X-X, Fig. 1, the slot 86 in the link bar 84 permitting the lever 15 to be swung into this position without affecting the knife carrying head operating mechanism. This forward movement of the lever 15 will release

the brake and, at the same time, start the motor. The bed will travel rearwardly underneath the shaving knife and as it approaches the limit of its rearward movement, its abutment 101 will engage the lug 70 99 of the bar 96 thus rocking the arm 95 in a direction to move the cam 90 into position to apply the brake 87, 88, 89. This same rocking movement of the arm 95 will rock the shaft 16 a sufficient distance to 75 swing the controlling lever 15 rearwardly into its neutral position, thus stopping the motor.

Furthermore, as the reciprocating bed 80 nears the limit of its rearward movement, the front stop 71 thereon will engage the arm 75 and move it rearwardly a sufficient distance to rock the shaft 52 for causing its eccentric portions 53, 54, to move upwardly to permit the springs 67, 68, to lift the knife 85 carrying head 27 away from the reciprocating bed 4. If, at any time during the rearward movement of the bed 4, it is desired to stop the shaving operation, the lever 69 can be raised by hand thus permitting the 90 spring 67, 68, to lift the knife carrying head and through the link connection 84 swing the controlling lever 15 into its intermediate position to stop the motor. After the reciprocating bed reaches the limit of its rearward movement and the knife carrying head is raised, the controlling lever 15 may be moved rearwardly into the position indicated by the line Y-Y of Fig. 1, thus releasing the brake and reversing the motor. 95 As the bed approaches the limit of its forward movement, the abutment 102 will engage the lug 100 of the bar 96 and swing the uprising arm 95 forwardly a sufficient distance to move the double faced cam 90 100 into position to apply the brake. This movement of the arm 95 will also rock the shaft 16 a sufficient distance to move the controlling lever 15 into its intermediate 105 position, thus stopping the motor. 110

By the construction, form and arrangement of the several parts, as herein shown and described, it will be seen that by providing a positive limit for the downward movement of the knife carrying head and 115 providing springs for raising the same, the head will be held rigidly against movement when in its lowered position during the shaving operation, thus permitting the adjustment of the knife carrying member with 120 the utmost accuracy.

Furthermore, by providing the springs 35, 36, around the adjusting screws 29, 30, all lost motion is taken up at this point and a micrometer adjustment of the knife carrying member may be obtained after an approximate adjustment thereof has been obtained. 125

It will furthermore be seen that both an automatic means is provided for raising the 130

knife carrying head and a manually operated means is provided for obtaining this movement.

Parts of the mechanism shown and described but not claimed herein relating more particularly to the knife carrying head and its operating devices, form the subject matter of a divisional application filed by me on the 31st day of October, 1910, its serial 10 number being 589995.

What I claim is:

1. In a machine of the character described, a knife carrying head, head raising and lowering mechanism, a reciprocating bed, a brake therefor, brake applying mechanism and a common manually operated lever connected to both the head raising and lowering mechanism and the brake applying mechanism for operating them.
2. In a machine of the character described, a knife carrying head, head raising and lowering mechanism, a reciprocating bed, a brake therefor, brake applying mechanism, means controlled by the bed for automatically operating the brake applying mechanism as the bed reaches predetermined points in its reciprocatory movements, and a manually operated lever connected to the head raising and lowering mechanism and 20 to the brake applying mechanism.
3. In a machine of the character described, a knife carrying head, head raising and lowering mechanism, a reciprocating bed, a brake therefor, brake applying mechanism, means controlled by the bed for automatically operating the head raising and lowering mechanism and the brake applying mechanism as the bed reaches predetermined points in its reciprocatory movements, and 25 a manually operated lever connected to the brake applying mechanism.
4. In a machine of the character described, a knife carrying head, head raising and lowering mechanism, a reciprocating bed, a brake therefor, brake applying mechanism, means controlled by the bed for operating the head raising and lowering mechanism and the brake applying mechanism as the bed reaches predetermined points in 30 its reciprocatory movements and a manually operated lever connected to the head raising and lowering mechanism and to the brake applying mechanism.
5. In a machine of the character described, a knife carrying head, head raising and lowering mechanism, a reciprocating bed, a motor for driving it, and means controlled by the bed for automatically operating the head raising and lowering mechanism and stopping the motor as the bed reaches predetermined points in its reciprocatory movements.
6. In a machine of the character described, a knife carrying head, head raising 60 and lowering mechanism, a reciprocating

bed, a motor for driving it, means controlled by the bed for automatically operating the head raising and lowering mechanism and for stopping the motor as the bed reaches predetermined points in its reciprocatory movements and a manually operated device connected to the head raising and lowering mechanism for raising and lowering the head at pleasure. 70

7. In a machine of the character described, a knife carrying head, head raising and lowering mechanism, a reciprocating bed, a motor for driving it, and means controlled by the bed for automatically operating the head raising and lowering mechanism and stopping the motor as the bed reaches predetermined points in its reciprocatory movements, and a manually operated device for stopping the motor at pleasure. 75

8. In a machine of the character described, a knife carrying head, head raising and lowering mechanism, a reciprocating bed, a motor for driving it, means controlled by the bed for automatically operating the head raising and lowering mechanism and stopping the motor as the bed reaches predetermined points in its reciprocatory movements and a manually operated device for operating the head raising and lowering mechanism and for stopping the motor at 85 pleasure. 90

9. In a machine of the character described, a knife carrying head, a reciprocating bed, a brake therefor, brake applying mechanism, driving means for the bed, a driving means controlling lever and means controlled by the bed connected to the brake applying mechanism and the driving means controlling lever for applying the brake and stopping the driving means as the bed reaches predetermined points in its reciprocatory movements. 100

10. In a machine of the character described, a knife carrying head, a reciprocating bed, a brake therefor, brake applying mechanism, driving means for the bed, a driving means controlling lever, means controlled by the bed connected to the brake applying mechanism and the driving means controlling lever for applying the brake and stopping the driving means as the bed reaches predetermined points in its reciprocatory movements and a manually operated device connected to the brake applying mechanism. 110 115

11. In a machine of the character described, a knife carrying head, a reciprocating bed, a brake therefor, brake applying mechanism, driving means for the bed, a driving means controlling lever, means controlled by the bed connected to the brake applying mechanism and the driving means controlling lever for applying the brake and stopping the driving means as the bed reaches predetermined points in its reciprocating 120 125 130

catory movements, and a manually operated device connected to the driving means controlling lever.

12. In a machine of the character described, a knife carrying head, a reciprocating bed, a brake therefor, brake applying mechanism, driving means for the bed, a driving means controlling lever, means controlled by the bed connected to the brake applying mechanism and the driving means controlling lever for applying the brake and stopping the driving means as the bed reaches predetermined points in its reciprocatory movements, and a manually operated device connected to the brake applying mechanism and to the driving means controlling lever.
13. In a machine of the character described, a knife carrying head, head raising and lowering mechanism, a reciprocating bed, a brake therefor, brake applying mechanism, driving means for the bed, a driving means controlling lever and means controlled by the bed connected to the head raising and lowering mechanism, the brake applying mechanism and the driving means controlling lever for operating the several parts as the bed reaches predetermined points in its reciprocatory movements.
14. In a machine of the character described, a knife carrying head, head raising and lowering mechanism, a reciprocating bed, a brake therefor, brake applying mechanism, driving means for the bed, a driving means controlling lever, means controlled by the bed connected to the head raising and lowering mechanism, the brake applying mechanism and the driving means controlling lever for operating the several parts as the bed reaches predetermined points in its reciprocatory movements and a manually operated device connected to the head raising and lowering mechanism, the brake applying mechanism and the driving means controlling lever for operating the said parts at pleasure.

15. In a machine of the character described, a knife carrying head, a reciprocating bed, means for driving the bed in either direction, a driving means controlling lever, a brake for the bed and means controlled by the bed for automatically bringing the controlling lever into its neutral position to stop the driving means and for applying the brake as the bed reaches predetermined points in its rearward and forward movements.

16. In a machine of the character described, a knife carrying head, a reciprocating bed, means for driving the bed in either direction, a driving means controlling lever, means controlled by the bed for automatically bringing the controlling lever into its neutral position as the bed reaches predetermined points in its rearward and forward movements, and a manually controlled lever for raising and lowering the knife carrying head, said lever having a lost motion connection with the driving means controlling lever for bringing the driving means controlling lever into its neutral position when the knife carrying head is manually raised.

17. In a machine of the character described, a knife carrying head, a reciprocating bed, means for driving the bed in either direction, a driving means controlling lever, means controlled by the bed for automatically bringing the controlling lever into its neutral position to stop the driving means and for raising and lowering the head as the bed reaches predetermined points in its rearward and forward movements and a manually controlled lever for raising and lowering the head, said lever having a lost motion connection with the driving means controlling lever for bringing the controlling lever into its neutral position when the head is manually raised.

18. In a machine of the character described, a knife carrying head, a reciprocating bed, a brake therefor, means for driving the bed in either direction, a driving means controlling lever, means controlled by the bed for automatically bringing the controlling lever into its neutral position to stop the driving means, for applying the brake and for raising and lowering the head as the bed reaches predetermined points in its rearward and forward movements and a manually controlled lever for raising and lowering the head, said lever having a lost motion connection with the driving means controlling lever for bringing it into its neutral position as the head is manually raised.

In testimony, that I claim the foregoing as my invention, I have signed my name in presence of two witnesses, this nineteenth day of July, A. D. 1909.

HOWARD M. BARBER.
